FLUID CONTAINER CAP LOCK

Irving H. Minkow and Larry W. Kaniewski,
South Bend, Ind.

Application November 17, 1938, Serial No. 241,038

1 Claim. (Cl. 292—207)

This invention relates to fluid container cap locks, and has for the primary object the provision of a device of this character which may be readily released by a remote control whenever it is desired to refill the container.

With this and other objects in view, the invention consists in certain novel features of construction, combination and arrangement of parts to be hereinafter more fully described and claimed.

For a complete understanding of our invention, reference is to be had to the following description and accompanying drawing, in which—

Figure 1 is a fragmentary side elevation illustrating a closure cap constructed in accordance with our invention and showing the same adapted to a portion of a neck of a container.

Figure 2 is a fragmentary vertical sectional view showing the remote control for the closure cap.

Referring in detail to the drawing, the numeral 5 indicates a filling neck of a container or tank such as employed on a motor vehicle for the fuel for the engine of said vehicle. The neck 5 has the usual inwardly extending flange 6. To permit easy filling of the tank or container with fluid and to prevent unauthorized removal of the fluid or the waste thereof, the present invention is adapted to the neck 5 and consists of a sleeve 7 fitting over a portion of the neck 5 with a tight fit and has an internal flange 8 resting on the flange 6. Rings 9 are arranged in the sleeve, one of which engages under the flange 6 and the other rests upon the flange 8 and are detachably connected by bolts 10. The sleeve 7 has hinged thereto a cap 11, the hinge for the cap being indicated by the character 12. When the cap is in a closed position and locked by a means which will be hereinafter described in detail it is impossible for the bolts 10 to be removed in order that the sleeve 7 be freed from the neck 5.

A sealing disc 13 is mounted on the inner face of the cap 11 and has a limited sliding movement relative to the cap. The sealing disc 13 is spring influenced away from the cap 11 by a coil spring 14 having engagement with the disc 13 and the cap 11. When the cap is swung into a closed position the disc 13 engages with the sleeve 7 and thereby provides an effective seal between the cap and the sleeve to prevent evaporation of the contents of the tank or container or the spilling of the contents therefrom. The spring 14 also acts to move the cap into a partly open position when the latter is released.

A latch member 15 is pivoted on the cap 11, as shown at 16, and is located opposite to the hinge

12 and is provided with a projection 17 to engage with a keeper 18 formed on the sleeve 7. The keeper 18 is formed by providing a notch 19 in the sleeve in which the extension 17 may lie when in engagement with the keeper 18 and has a cam face. The notch 19 and keeper 18 are formed in an enlargement 20 provided on the sleeve 7. The enlargement 20 is provided with a chamber 21 opening outwardly through the lower edge thereof. The enlargement 20 is also provided with an opening 22 which communicates with the chamber 21 and through which a hook-shaped extension 23 on the latch element 15 may extend when the latch element is in securing position.

One end of a cylinder 24 is mounted in the chamber 21 and has an opening 25 aligning with the opening 22 to permit the hook-shaped extension 23 to enter the cylinder. A plunger 26 is slidable in the cylinder 24 and is provided with a keeper portion 27 to engage with the hook-shaped extension 23 of the latch element for securing the latch element in a position to lock the cap in a closed position. The plunger 26 is influenced in one direction by a spring 28 located in the chamber 21 and is cut away to provide a reduced neck-like portion and providing a substantially conical shaped strike face 21' and a cup shaped portion 22' having a beveled strike face 23'.

The closed end of the cylinder has connected thereto a flexible pipe 29 which is in turn connected to a pump 30. The pump 30 is remotely located to the cap and the tank to which the cap is adapted. For instance, the pump 30 may be located within the body of an automobile in convenient reach of the driver so that on operation of the pump air will be displaced therefrom into the cylinder for actuating the plunger 26 into a position to release the latch element 15 and permit the cap to be opened. When the latch is returned to latching position it automatically engages with the keeper 27 of the plunger and thereby brings about a positive locking of the cap in a closed position.

The pump 30 consists of a cylinder 31 suitably mounted in the motor vehicle and has removably mounted thereon an apertured cap 32. A piston 33 is operable in the cylinder 31 and includes a foot engaging portion 34 which extends through the apertured cap 32. The operator or driver of the motor vehicle can readily depress the piston 33 by engaging the foot with the portion 34 of the piston. The movement of the piston 33 under the influence of the operator's foot expels air from the pump into the cylinder 24 causing a

sliding movement of the plunger 26 against the action of the spring 28. This sliding movement of the plunger frees the latch element 15 so that the cap will be partly opened by the spring 14. As soon as the operator's foot is removed from the piston 33, the spring 28 restores the plunger 26 to its initial position. The air in the cylinder 24 is displaced therefrom by the movement of the plunger 26 under the influence of the spring 28 and forces the piston 33 in the cylinder 31 back to its normal position. When the plunger 26 is returned to normal position by the influence of the spring 28, said plunger is positioned to bring about locking of the latch element as soon as said latch element is moved into locking position.

The extension 17 rides on the cam face of keeper 18 to relieve the piston 26 of any forces which would tend to bind said piston by the hook-shaped extension 23 during movement of the latch member 15. The cam face of the keeper 18 is such that latch member 15 will remain in engagement therewith due to the extension 17 riding past dead center position on said cam. A locating screw 24' is provided for holding the piston 26 in proper position when the latch member 15 is in unlocking position so that the latter may be easily snapped into locking position. The hook-shaped extension 23 rides the strike face 23' of the piston for moving the piston 26 upwardly when the latch member 15 moves into locking position. Also the strike face 21' acts to kick the latch member outwardly or toward releasing position on the actuation of the piston 26 by the pump 30. In operation, movement of the remote control pump 30 moves the piston upwardly to clear the hook-shaped extension 23 and the latter rides the strike face 21' which moves the latch member outwardly sufficient to pry the extension 17 off of the cam or past the dead center position so that it may ride

on the fast releasing portion of the cam of the keeper 18, permitting the spring 14 tending to urge the cover into partly open position to fully release the latch member 15.

5 The sleeve 7 is provided with a vent opening 25'.

While we have shown and described the plunger as being operated by pneumatic means, it is to be understood that through a simple rearrangement of parts the plunger may be electrically actuated.

10 It is believed that the foregoing description, when taken in connection with the drawing will fully set forth the construction and advantages of this invention to those skilled in the art to which such a device relates, so that further detailed description will not be necessary.

15 What is claimed is:

Locking means for a closure cap member 20 hinged to a sleeve on the neck of a tank, said means comprising a hollow boss on said sleeve forming a socket therein, a cylinder fixed at one end in said socket to extend therefrom, said socket and cylinder having a pair of registering 25 openings therein, a latch bar having a lateral keeper lug thereon and adapted to be hinged to said cap member for swinging movement in the closed position of said member in opposite directions to project said lug through said openings 30 in said cylinder and to retract the same, respectively, and a plunger in said cylinder operative in opposite directions and interlocking with said lug under movement thereof in one direction to prevent retraction of the lug and thereby 35 latch said bar, said plunger under movement thereof in the opposite direction breaking the interlock and subsequently camming said lug out of said cylinder to unlatch said bar.
